ATTORNEY

UNITED STATES PATENT OFFICE.

FRANK A. LUNDQUIST, OF BROOKLYN, NEW YORK.

BURGLAR-ALARM.

1,051,962.

Specification of Letters Patent.

Patented Feb. 4, 1913.

Application filed February 11, 1911. Serial No. 607,962.

To all whom it may concern:

Be it known that I, FRANK A. LUNDQUIST, a citizen of the United States, residing at Brooklyn, in the county of Kings and State 5 of New York, have invented new and useful Improvements in Burglar-Alarms, of which the following is a specification.

This invention relates to alarms, and more particularly to the class of burglar alarm 10 devices.

The particular object of the invention is the provision of a burglar alarm device comprising a hollow cylinder having a plurality of striker elements provided thereon, attaching means arranged at opposite ends of the cylinder adapted to be connected to a window frame and one of its sashes, and spring tension means adapted to rotate the cylinder so as to cause the knocker elements to strike 20 the pane of glass arranged within the said sash.

With these and other objects in view, as will appear as the description proceeds, the invention comprises the various novel features of construction and arrangement of parts which will be hereinafter more fully described and set forth with particularity in the appended claims.

Referring more particularly to the drawings, Figure 1 is an elevation of the alarm device shown in applied position, Fig. 2 is a vertical sectional view through the device, and Fig. 3 is a top plan view of Fig. 2.

Similar reference characters are used to 35 denote like parts throughout the specification and the accompanying drawings.

Referring to the drawings, the device will be seen to consist of a hollow cylinder 5, the lower end of which is threaded exteriorly 40 to receive a cap or bottom 6, which latter is provided centrally with an aperture through which projects the shank 7 of a swivel 8. The lower outer end of the shank of the swivel is provided with an eye to 45 which is connected one end of a hook 9. Secured to the window sill is a screw eye or other suitable device 10 with which the opposite end of the hook 9 is adapted to engage to maintain the device in position. The 50 upper end of the cylinder 5 is closed, as shown at 11, and is provided centrally with a square aperture 12. Arranged within the cylinder adjacent the lower end thereof is a disk 13 secured to the cylinder by any suitable means, such as screws 14. The disk 13 is provided centrally upon its upper face

with an upstanding boss 15 which latter is provided with a socket adapted to receive and support the lower end of a spindle 16. The spindle 16 has its upper end portion 60 squared, as shown at 16^a, and the inner portion thereof is adapted to slidably fit and seat within the aperture 12 in the upper end 11 of the cylinder. The spindle is provided adjacent the inner end of the upper squared portion with a reduced circular shank 17.

Surrounding the spindle 16 is a coiled tension spring which has its lower end secured to the boss 15 of the disk 13 and the 70 upper end thereof is secured to a flange 19 adjacent the reduced portion 17 at the upper end of the spindle, and is in spaced relation to the inner face of the top 11 of the cylinder. The upper squared portion 16^a of 75 the spindle is provided with a thumb nut 20 which latter normally rests upon the upper surface of the top 11 of the cylinder. The upper end of the squared portion 16^a is provided with an aperture to which is connected 80 a hook 21, the latter having connected thereto one end of a chain 22, the opposite end of the chain being detachably connected with a projection 22' upon the inner face of 85 the window sash.

Provided on the outer surface of the cylinder 5 are a plurality of swinging flexible striker elements 23, each of which comprises, preferably, a ball of suitable material and a chain or other flexible element 90 secured to the ball and to the outer surface of the cylinder 5 whereby said ball may have a free swinging movement.

It will be seen by reference to Fig. 1 that since the device is arranged adjacent the 95 pane of glass of the sash that should the latter be raised in an attempt to allow a person to pass through the window or for some other reason, the spindle 16 will be lifted by reason of the connection between the upper end thereof and the sash. By this movement the lower end of the squared portion 16^a is disengaged from the aperture 12 in the upper end of the cylinder and the reduced portion 17 is brought into engagement with the aperture whereby the spring 18 carried by the spindle 16 will exert its tension to revolve the cylinder 5 around the spindle thus causing the flexible striker elements to swing outwardly 100 through the medium of the centrifugal force imparted thereto and successively strike the 110

adjacent window pane. It will be apparent by reason of the reduced shank portion 17 and the swivel 8 that the cylinder 5 will be free to rotate upon and around the spindle 5 16. After the device has been set off the spindle is lifted so that the reduced portion thereof engages within the aperture 12 whereby the thumb nut 20 may be grasped and revolved to replace the tension upon 10 the spring surrounding the spindle. After sufficient tension has been placed upon the spring the spindle is allowed to descend to its normal position so that the lower end of the squared portion 16^a rests within the upper aperture 12, thus preventing the cylinder against rotation.

From the foregoing description, taken in connection with the accompanying drawings, the advantages of construction and the 20 method of operation will be readily apparent to those skilled in the art to which the invention relates, and while I have described the principle of operation of the invention, together with the device which is 25 now considered to be the best embodiment thereof, I desire to have it understood that such changes of construction may be made when desired as are within the scope of the appended claims.

30 What I claim as new is:—

1. A burglar alarm device comprising a hollow cylinder, the opposite ends of which are closed and provided with a round and a square aperture respectively, a plurality 35 of striker elements pivotally supported upon the cylinder, a spindle arranged within the cylinder and provided at its upper end with a squared portion, and a reduced circular

portion adjacent the inner end of the squared portion, said squared portion adapted to normally seat within the square aperture in the end of the cylinder, a spring surrounding the spindle having one end connected to the spindle and the other end to the cylinder, a swivel arranged within the 45 aperture at the lower end of the cylinder, and means connected with the swivel and the outer end of the spindle whereby the device may be supported in operative position.

2. A burglar alarm device comprising a 50 hollow cylinder having a squared aperture in one end, a plurality of striker elements pivotally supported upon the cylinder, a disk arranged within the cylinder and connected thereto adjacent one end and provided with an upstanding hollow boss, a spindle arranged within the cylinder and having its lower end pivotally supported within the boss, the upper end of the spindle being squared and projecting through 55 the squared aperture in the end of the cylinder, said spindle being reduced to form a circular shank adjacent the squared portion, a tensioned coiled spring surrounding the spindle and connected to the spindle and the disk, means for connecting the outer end of the spindle to a window sash, and means for swivelly connecting the opposite end of the device to a window frame.

60 In testimony whereof I affix my signature 70 in presence of two witnesses.

FRANK A. LUNDQUIST.
